UNITED STATES PATENT OFFICE

162,679

DEODORIZER OR SIMILAR ARTICLE

Richard A. Munnecke, Pasadena, Calif.

Application September 7, 1949, Serial No. 4,889

Term of patent 3½ years

(Cl. D16—2)

To all whom it may concern:

Be it known that I, Richard A. Munnecke, a citizen of the United States and residing at Pasadena, in the county of Los Angeles, and State of California, have invented a new, original, and ornamental Design for a Deodorizer or Similar Article, of which the following is a specification, reference being had to the accompanying drawing, forming part thereof.

In the drawing is illustrated a view in perspective of a deodorizer embodying my new design, the rear being similar to the front as shown, with the lower end portion similar to the top portion as illustrated.

I claim:

The ornamental design for a deodorizer or similar article, substantially as shown and described.

RICHARD A. MUNNECKE.
